UNITED STATES PATENT OFFICE.

WILLIAM P. BIGELOW, OF NATICK, MASSACHUSETTS, ASSIGNOR TO THE MERCHANTS' STORE SERVICE COMPANY, OF PORTLAND, MAINE.

CASH AND PACKAGE CARRIER.

SPECIFICATION forming part of Letters Patent No. 330,869, dated November 24, 1885.

Application filed August 3, 1885. Serial No. 173,318. (No model.)

To all whom it may concern:

Be it known that I, WILLIAM P. BIGELOW, a citizen of the United States, residing at Natick, in the county of Middlesex and Commonwealth of Massachusetts, have invented certain new and useful Improvements in Cash and Package Carriers; and I hereby declare that the same are fully described in the following specification and shown in the accompanying drawings.

My invention consists in various improvements relating to cash and package systems, and more especially to those in which there is used a positively-fixed track and a traction-belt to propel a carriage on said track.

In the accompanying drawings, Figure 1 is a perspective view of a stationary track or single supporting-way provided with a traveling or traction belt with my improved carriage and appliances for operating the same, showing also how the traction-belt may be operated by steam-power. Fig. 2 is a perspective view showing the means for operating the traction-belt by hand-power. Fig. 3 is a sectional view of my improved track, together with the device for releasing the basket from the carrier. Fig. 4 is a plan end view of the device by which I connect the basket with the carriers. Fig. 5 is a sectional view of the same. Fig. 6 is a rear elevation of my improved carriage resting on the track or supporting-way, which consists simply of an L-shaped strip of any suitable material. Fig. 7 is a view, partly in section, of the device for connecting the basket with the carriage in place in the carriage. Fig. 8 is an elevation, partly in section, showing the operation of releasing the device which holds the basket upon the arms of the carriage. Fig. 9 is an elevation, partly in section, showing the track I preferably use. Fig. 10 is a top plan view of my improved carriage. Fig. 11 is a perspective view of the same.

D represents the frame of my improved carriage, which is provided with two wheels, C C', preferably made of rawhide, to run on the top of the vertical arm of the track F or X, while E is a wheel, preferably of rawhide, adapted to steady the carriage by coming in

contact with the lower side of the horizontal 50 arm of the track F or X. This is clearly shown in Figs. 6 and 9.

A and B are two arms or flanges connected with the carriage D, arranged to readily receive the arm L of the basket or any other 55 suitable device for carrying a package. The arm L is provided with two small levers, as shown in Figs. 4, 5, 7, and 8, M M', which are held firmly at right angles to the arm L unless the triggers N N' are pressed apart or 60 separated from each other, when the levers M M' will assume a vertical position. Any suitable device—such as a spring, S—I use in connection with the triggers N N'.

O is simply the frame-work which holds the 65 levers M M' and the mechanism for operating the same.

H is a V-shaped wedge connected to the bent arm I, which is connected to the supporting way or track, as shown in Fig. 3. This 70 V-shaped wedge I preferably use to operate the levers M M' by means of triggers N N'.

J is a traction-belt, to which I connect the carriage D by any suitable means, and which is operated by passing around the grooved 75 pulleys R R'.

I have shown in Figs. 1 and 2 the pulleys R connected to a vertical shaft, P, which can be operated by steam-power by means of the gear-wheels S S' and the pulley T, or by hand-power by means of the gear-wheels S S' and the hand-gears T T'.

F' F' are simple supports by which the supporting-way F is connected to the ceiling or upper part of the room.

Q is a bracket for supporting the grooved wheel R'.

K is a shelf placed beneath an arm, I, for catching the basket when it automatically drops from the carriage.

I preferably use a track of the construction shown in section in Fig. 3, where F represents an L-shaped strip, preferably of metal—such as iron—while X is a thin strip, preferably of wood, attached to the L-shaped strip. 95 This may be done by bolts or in any effectual way. The carriage-wheels move on the upper and under edges of the strip X or L-strip, as

shown in Figs. 6 and 9. By using the wood strip I obtain a light and noiseless track.

The peculiar construction of the track has many advantages. It keeps always in perfect 5 position, and is easily handled.

In Fig. 1 I have shown two baskets connected by the arm L to my improved carriage. These baskets may be provided with a handle or not.

10 In operating my improved system I preferably use steam-power as a motor, and I cause the traction-belt J to move continuously at a suitable speed, drawing with it any number of carriages D D, which are all alike, and 15 which may be placed any suitable distance apart. Any one of these carriages D D is adapted, by means of its arms A B, to receive the arm L, and thereby support and carry the basket. As the carriages D D are continually 20 passing around the track, the salesman or cashier who desires to send the parcel from one station to another has simply to hold the basket up, placing the arm L against the track F or X, and the carriage, as it approaches, 25 will receive the arm L between its flanges A B. The levers M M', being horizontal during this operation, support the basket at the rear of the flanges A B, and are kept in place by the notches a b. The basket is also carried from 30 the point where it is automatically disconnected by the triggers N N' coming in contact with its corresponding wedge, H. It will be readily seen that by varying the length of the triggers N N' and the device H they will come 35 in contact or not with each other.

In a system of this kind there may be two or more salesmen's stations, each of which has a carrier provided with triggers, which are only operated at its particular station and at 40 the cashier's station. I use two supporting-ways, that I may have, preferably, at one end of these supporting-ways a cashier's desk, and between each end of the supporting-ways one or more salesmen's stations.

45 I operate my improved system by having the salesman attach the carrier or basket to the carriage as it is moving in the direction of the cashier's desk, where it is discharged, and by having the cashier reattach the basket and 50 send it to the particular salesman to whom it belongs on the other supporting-way by a carriage moving on that way to the salesman. It will be thus seen that the salesman when he desires to send the basket to the cashier's desk 55 attaches it to a carriage, for illustration, in front of him, and receives it on its return from the cashier on the supporting-way back of himself.

In Fig. 1 the arrow x indicates the supporting-way on which the carriage moves to the cashier's desk—supposed to be at the point I', near the shaft P—while the arrow y represents the supporting-way upon which the carriage moves when it returns from the cashier's 65 desk to be discharged at a salesman's station, as at I or I', near the support F'. I preferably

have a basket for each salesman's station, the trigger of whose handle is only operated at its station and at the cashier's station. Thus it will be readily seen that a basket connected 70 by a salesman to a carriage moving to the cashier's desk, as at a point, x, opposite the discharging-station I', Fig. 1, will pass up the track to the cashier's station I', next to the shaft P, where it will be automatically discharged from the carriage, while a basket connected at the cashier's desk I', next to shaft P, will pass on the other supporting-way in the direction of the arrow y, and will be automatically discharged at its proper salesman's 80 station, as I'.

In order to create no confusion at the cashier's desk, I have each of the baskets or carriers lettered or numbered to correspond with the particular station to which they belong. 85 It will be noticed that a basket can be connected to a carriage at any point in the track, and that it will continue to travel with the carriage till it arrives at a point where the triggers of its handle are operated upon, when 90 it will be discharged. As at the cashier's station all the baskets are to be discharged, one device, H, may be constructed of sufficient length to operate all the triggers of the different handles. I have shown a shelf, K, on 95 which the basket may drop as it is discharged at I over it. There may be used for catching the basket several other things—such as a wire-netting, or a pouch made of cloth or any suitable material. This shelf or pouch should be placed at sufficient distance below the track to allow the other baskets to pass over it.

In setting up my improved system I preferably place the tracks so that one is next to the shelving, back of the counter, and its parallel track just over the edge of the counter. With this arrangement I attach the shelf or pouch K to the shelving. The traction-cord J, if the system is operated by steam-power, is intended to be always in motion, so that I preferably have the salesman attach the basket to the carriage as it is passing on the track over the counter. The basket is then carried to the cashier's desk and automatically discharged. When the goods have been packed and change 115 made, the basket is attached to any one of the passing carriages, and is taken on the track next to the shelving back to the salesman, where it is automatically discharged.

Having now fully described my invention, 120 what I desire to claim is—

1. In a store-service system, supporting-ways between the cashier's desk and the salesmen's stations, in combination with a traction-belt provided with a series of carriages having 125 wheels arranged to run on the upper and lower edge of said ways, substantially as set forth.

2. In a store-service system, a supporting-way, a traction-belt, a series of carriages attached to said belt, carriers provided with 130 arms having levers to support said carriers and discharge them, triggers and a wedge to

operate the said levers, whereby the carriers are automatically discharged at the cashier's desk and at the salesmen's stations, substantially as described.

5 3. In a store-service system, the combination, with a track, of a traction-belt and carriages provided with wheels arranged to run on the upper and lower side of said track, which consists of an L-shaped strip of any suitable material, substantially as described.

10 4. The combination, with a traction-belt and its carriages, of the supporting-way, baskets, and shelf or pouch to receive the basket when it is disconnected from the carriage, substantially as described.

15 5. In a store-service system, a track consisting of the combination of a metallic supporting-way having a non-metallic rail, for the wheels of the carriage to come in contact with, as and for the purpose substantially as described.

20 6. In a store-service system, a carriage for supporting a basket or carrier, consisting of a frame provided with wheels adapted to run on the upper and lower sides of a supporting-way, and also provided with flanges arranged to receive the arm or handle of a carrier, substantially as described.

25 7. In a store-service system, a basket or carrier, in combination with an arm provided with a mechanism for connecting it with the carriage which transports the carrier, the said mechanism consisting of two levers provided with triggers, which are operated by coming in contact with a wedge, and said wedge, whereby the carrier is supported and automatically discharged, substantially as described.

30 8. In a store-service system provided with a supporting-way and a traction-belt, and having two or more salesmen's stations and a cashier's desk, a carrier or basket for merchandise and cash for each station, which carrier or

basket is automatically discharged from the supporting-way only at its own station and the cashier's desk, substantially as described. 45

9. In a store-service system, the carrier having an arm provided with mechanism consisting of the levers M M', the triggers N N', and spring S, in combination with the carriage having flanges A B, whereby the carrier is supported and discharged, substantially as described. 50

10. In a store-service system, the carrier having an arm provided with mechanism consisting of the levers M M', the triggers N N', and spring S, in combination with the wedge or wedges arranged to operate said triggers, and a carriage having the flanges A B, whereby the carrier is supported and automatically discharged, substantially as described. 55

11. A store-service system consisting of a supporting-track, a traction-belt, carriages D, arranged to run on said track and propelled by said belt, carriers provided with arms arranged to be supported on said carriages and to be automatically discharged therefrom, and arms arranged to operate on the supporting and discharging mechanism of the carrier, whereby each carrier is discharged at its own station and at the cashier's desk only, substantially as described. 60

12. A store-service system in which each station has a carrier so connected to the traction-belt which carries it to and fro between its own station and the cashier's desk that it is only discharged at its own station and at the cashier's desk, substantially as described. 70

In witness whereof I have hereunto set my hand.
